US00D660893S

(12) **United States Design Patent**
Wang

(10) **Patent No.:** **US D660,893 S**
(45) **Date of Patent:** **** May 29, 2012**

(54) **CONTACT LENS**

(75) Inventor: **Daozhi Wang**, Webster, NY (US)

(73) Assignee: **Bausch & Lomb Incorporated**,
Rochester, NY (US)

(**) Term: **14 Years**

(21) Appl. No.: **29/339,573**

(22) Filed: **Jul. 2, 2009**

(51) LOC (9) Cl. **16-06**

(52) U.S. Cl. **D16/101**

(58) **Field of Classification Search** D16/101,
D16/300–342, 900; D29/109–110; D24/110.2;
351/41, 44, 51–52, 62, 158, 92, 103–123,
351/140, 153, 45–46, 162; 2/426–432, 447–449,
2/441, 434–437, 13, 15; D21/483, 659–661

See application file for complete search history.
